UNITED STATES PATENT OFFICE.

ALEXANDER L. BOWER, OF PHILADELPHIA, PENNSYLVANIA, ASSIGNOR
TO THOMAS POTTER SONS & COMPANY, INCORPORATED, OF SAME
PLACE.

DESIGN FOR A FLOOR-CLOTH.

SPECIFICATION forming part of Design No. 84,461, dated April 30, 1901.

Application filed April 2, 1901. Serial No. 54,106. Term of patent 33 years.

To all whom it may concern:

Be it known that I, ALEXANDER L. BOWER, a citizen of the United States, residing at Philadelphia, in the county of Philadelphia and State of Pennsylvania, have invented and produced a new and original Design for Floor-Cloths, of which the following is a specification, reference being had to the accompanying drawing, forming part thereof.

As shown in the drawing, the leading features of my design are comprised in a checkered ground composed of the squares A and A', of contrasting colors, with the representation thereon of the floral bouquet B, composed of flowers of different colors and varieties. Surrounding the bouquet are smaller nosegays made by combining the parts there-

of C and C', the drawing showing a full repeat of the pattern printed upon the floor-cloth.

Having described my invention, what I claim as new, and desire to secure by Letters Patent, is—

The design for a floor-cloth substantially as herein shown and described.

In testimony whereof I have signed my name to this specification, in the presence of the two subscribing witnesses, this 30th day of March, 1901.

ALEXANDER L. BOWER.

Witnesses:

THOMAS S. GATES,
PERCIVAL H. GRANGER.
